BY Edwin H. Remond,

HIS ATTORNEY.

UNITED STATES PATENT OFFICE.

LEO PRANGE, OF BROOKLYN, NEW YORK.

DESIGN FOR A BUTTON.

SPECIFICATION forming part of Design No. 21,314, dated January 26, 1892.

Application filed December 18, 1891. Serial No. 415,549. Term of patent 3½ years.

To all whom it may concern:

Be it known that I, LEO PRANGE, of Brooklyn, Kings county, and State of New York, have originated and produced a new Design for Buttons, of which the following is a specification.

I will describe a button embodying my design.

In the accompanying drawings, Figure 1 is a front view of a circular button embodying my design. Fig. 2 is a perspective side view thereof.

My design comprises a group of figures representing jewels arranged in rows so that the upper part will have the appearance of a curved line or of two diverging lines. As shown, this group of figures bears a resemblance to a crescent. From the extremities of the group of figures A a wavy line B, made up of figures representing small jewels, extends. In the central portion of the button

figures C, representing jewels, are grouped so as to resemble a flower. Below the figures C are figures D, representing jewels made in the form of leaves. The portion E of the button surrounding the figures C D and within the group of figures A and the line B is shown as covered with fine lines and as being somewhat wavy on the surface. Below the figures D are shown filigree figures F.

What I claim, and desire to secure by Letters Patent, is—

The design for a button, as herein shown and described.

In testimony whereof I have signed my name to this specification in the presence of two subscribing witnesses.

LEO PRANGE.
